UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed December 14, 1923. Serial No. 680,721.

To all whom it may concern:

Be it known that I, ALONZO E. RHOADES, a citizen of the United States, residing at Hopedale, in the county of Worcester and 5 State of Massachusetts, have invented an Improvement in Feeler Mechanisms for Looms, of which the following description, in connection with the accompanying drawings, is a specification, like characters on the 10 drawings representing like parts.

This invention relates to feeler mechanisms for looms whereby the operative condition of the loom is changed from time to time, and more particularly the present invention 15 relates to feeler mechanisms of the intermittent type.

In feeler mechanisms of the general type referred to the feeler is held in a frontward or inoperative position for periods of time 20 and is periodically released from said position to perform its detecting function, and should a working supply of filling be present in the shuttle on a detecting beat following movement of the feeler to its feeling position, 25 it is again moved frontwardly by the filling and held in frontward position for another interval of time. Should, however, the feeler detect a near approach to substantial exhaustion of the filling on a detecting beat, 30 it will remain in its feeling position and continue to detect the condition of the filling until substantial exhaustion thereof is reached, whereupon the feeler will operate to effect a change in the loom operation, such, 35 for instance, as replenishment of filling.

When the feeler is in operative or feeling position to detect the condition of the filling in the shuttle, the desired sensitiveness of the feeler should be such that it may properly function without injuriously effecting the filling during its period of operation. One of the important features of the present invention, therefore, consists in a feeler mechanism of the intermittent type wherein the feeler may sensitively cooperate with the filling when in feeling position, and when moved frontwardly by a working supply of filling on a detecting beat it may automatically pass into control of means for holding the feeler in its frontward retracted position.

Since one of the many purposes of the intermittent feeler is to prevent injury to the filling by recurring contacts with the filling 55 on detecting beats, it is important that the

feeler be moved into such inoperative or retracted frontward position during its periods of inactivity that it may not during such periods engage the filling at all. Another important feature of the present invention, 60 therefore, consists in a feeler mechanism wherein the feeler is given frontward movement in addition to that imparted by the working supply of filling on a detecting beat to retract the feeler from the position to 65 which it has been moved by the filling, so that on subsequent beats the feeler will not engage the filling.

In accordance with the present invention the feeler is held in its frontward or inoperative position by a detent which is tripped from time to time from a moving part of the loom such as the take-up, to release the feeler to the performance of its feeling function, and when the feeler is thus freed, the detent is locked in its inoperative position or out of engagement with the feeler, so that the feeler may act sensitively. In the present invention, also, when the detent is moved into its operative position to engage and hold the feeler in retracted position, the detent is given a movement to cause a further frontward retraction of the feeler from the position into which it has been moved by the working supply of filling. 85

The various features of the invention and new combination of parts will best be made clear from the following description and the accompanying drawings of one form of a feeler mechanism embodying the invention. 90

In the drawings:

Fig. 1 is a perspective view of the feeler side of a loom provided with the present invention, only such parts being shown as are necessary for a full understanding thereof; 95

Fig. 2 is a longitudinal section of the detent lock or holding means for retaining the detent in its inoperative position during periods of activity of the feeler; 100

Fig. 3 is an enlarged perspective view showing a feeler mechanism embodying the present invention, some of the parts being broken away, and the feeler being illustrated as held in its frontward retracted position 105 by the detent;

Fig. 4 is a sectional plan showing more particularly the detent movement for carrying the feeler frontwardly when the detent moves into its operative position; and 110

Fig. 5 is a view in perspective showing the relation of parts when the feeler has been released by the detent and the detent itself is held in its inoperative position.

The invention is shown as embodied in a feeler mechanism of the "side swipe" type wherein the feeler is moved in a direction longitudinally of the shuttle to effect replenishment of filling when that in the shuttle is substantially exhausted, and while the advantages of the invention are well manifested in such type of feeler mechanism, it is to be understood that the invention is not necessarily restricted thereto but may be employed in connection with any type of intermittent feeler mechanisms. In the present instance of the invention, also, the feeler mechanism is shown as contrived to effect replenishment of filling when that in the active shuttle is substantially exhausted, but since the replenishment mechanism and the details thereof form no special part of the present invention, it has not been deemed necessary to illustrate and describe these features except in so far as they are associated with the feeler mechanism.

The loom frame 1 is of usual construction and has mounted thereon the transverse or rock shaft 2 which extends transversely of the loom, and connected to the train of mechanism for rendering operative the feeler mechanism as usual in filling replenishing looms. Secured to and extending upwardly from the transverse or rock shaft 2 is an arm 3 to which is pivoted at 4 an actuator 5 the rear end portion 6 of which is adapted to be engaged by an operating member 7 when the filling is to be changed. The operating member 7 is conveniently formed as part of or is secured to the cam follower. The rear portion 6 of the actuator 5 is constituted as a member pivoted at 8 and provided with a finger 9 overlying the one arm 10 of a bell crank lever pivoted at 11, Fig. 1, and connected at 12 with a transmitter 13 which is itself connected to a slide 14.

Extending from the loom frame is the shipper stand 15 to which is connected a bracket 16 which may be conveniently secured to the shipper stand by an adjusting bolt 17.

The feeler stand 18 is connected to the supporting bracket 16 by a bolt 19 which passes through a slot 20 formed in the feeler stand, the construction being such that the feeler stand may be adjusted into its proper position.

The feeler stand has formed at the rear portion thereof the bearings 21 in which the slide 14 is movable laterally, and passing through an opening 22 in the slide is the feeler 23, the opening 22 being of larger dimensions than the feeler that the feeler may have some movement in the opening

without causing movement of the slide. The feeler has extending forwardly the feeler stem 24 which passes through a swivel block 25 mounted in a bracket 26 secured to the feeler stand, and interposed between the swivel block 25 and the bridge 27 secured to the feeler is a spring 28 normally tending to move the feeler rearwardly. The bridge 27 has the side members 29 which, as shown, may rest upon the top of the feeler stand. The parts so far described may be and substantially are the same as the corresponding parts in the patent to Edward S. Stimpson, No. 1,309,227, July 8, 1919.

In accordance with the present invention, the feeler is provided with a part adapted to be engaged by a detent for holding the feeler in its forward retracted position, and in the present instance said part is formed as a bar 30 which may be conveniently secured to the top of the feeler and providing at its rear end a shoulder or projection 31 adapted to be engaged by the detent to hold the feeler in its forward retracted position.

The lay 32 is provided with the shuttle box 33 adapted to receive the shuttle 34 containing the filling carrier or bobbin 35 on which the filling is wound, and as usual in this class of looms, the front wall of the shuttle box is provided with an opening 36 adapted to register with an opening 37 in the front wall of the shuttle when the latter is properly positioned in the detecting shuttle box. These parts may be as usual.

Extending from the loom frame, as shown in the present instance, projecting upwardly from the shipper stand is a bracket 38 on which is pivotally supported at 39 the detent for holding the feeler in its forward retracted position. In the present instance the detent is formed as a lever 40 having its front end portion 41 extending transversely over the top of the feeler, as indicated in Figs. 1 and 3. The other end 42 of the detent is extended laterally from the pivotal support 39 to be engaged by a tripping device, presently to be described, and the detent 40 is normally under the influence of a spring 43 tending to turn the detent into its operative position.

In accordance with the present invention, when the detent is in its operative position, as indicated in Fig. 3, the part or projection 31 carried by the feeler will engage the front side of the detent and hold the feeler in its forward retracted position and in order to release the feeler periodically a tripping device is provided. In the present instance the tripping device comprises a slide 44 mounted on a guide or box 45 secured to the rear portion of the shipper stand, and its lower end is connected at 46 with an arm 47 which extends downwardly and is jointed at 48 to a tripping lever 49 pivoted at 50 to

the loom frame or to a bracket 51 secured thereto. Surrounding the pivotal support 50 of the tripping lever 49 is a spring 52 normally tending to turn the tripping lever 49 in a clockwise direction, indicated in Fig. 1, and limited in such movement by a stop 53 which may be conveniently formed on the slide 44 to contact with the lower portion of the bearing or box 45, as indicated 10 in Figs. 1 and 3.

An arm 54 of the tripping lever extends into the path of movement of a lug 55 formed on or secured to one of the members of the train of take-up mechanism. In the 15 present instance, the trip lug 55 is shown as secured to the ratchet wheel 56 which, as common in take-up mechanisms, is given a rotary movement from a going part of the loom to take up the cloth as woven. It will 20 not be necessary herein to describe the train of take-up mechanism beyond what has already been said, because such mechanisms are now well-known. The construction is such that as the take-up mechanism is actuated to take up the cloth, the tripping lug 25 55 which moves in the direction of the arrow, Fig. 1, will engage the end 54 of the tripping lever after a predetermined number of picks and will lift the end 54 of the 30 tripping lever to thereby depress the slide 44 and through a hook portion 57 of the slide which engages the end 42 of the detent move the detent clockwise viewing Figs. 1 and 3, and thereby free the feeler to the 35 performance of its feeling function.

In accordance with one feature of the present invention, the detent when freed from engagement with the feeler is to be held or locked in its inoperative position 40 that it may not interfere with the sensitivity of the feeler during the performance of its feeling function.

The lock for thus holding the detent in its inoperative position may be variously 45 contrived, but in the present instance of the invention the lock is formed as a plunger 58, Figs. 2, 3 and 4, which is mounted in a casing 59 secured to the feeler stand. In the present instance the casing 59 is shown 50 as secured to the rear portion of the feeler stand and may be conveniently formed as a part of the cover plate 60 which confines the slide 14 in its bearings 21.

The stem 61 of the plunger, Fig. 2, extends frontwardly of the casing 59 and has secured thereto a lug 62 by means of a nut 63 and the lug 62 preferably extends downwardly and its lower portion 64 engages a 55 guide member 65 formed on or secured to the feeler stand. The lug 62, as shown, is disposed some distance in front of the bridge 27 and the bearing portions 29 thereof, the construction being such that should the feeler be moved frontwardly a predetermined amount, the lug 62 will be engaged

by the bearing portion 29 carried by the feeler and will cause the plunger 58 to be retracted, but when the feeler is released from the detent and moves rearwardly, the spring 66 within the casing 59 will cause the 70 plunger 58 to be moved rearwardly under the end of the detent and thereby hold the detent in its raised or inoperative position and out of engagement with the feeler, that the latter may perform its feeling functions 75 with the desired sensitiveness.

Should the feeler meet a working supply of filling in the shuttle on a detecting beat after it has been released by the detent and while the detent is locked in its inoperative 80 position, it will be moved frontwardly sufficiently far to cause the part or shoulder 31 on the feeler to pass forward under the detent, and when this relation of parts has been effected, the bearing 29 carried by the 85 feeler will engage the lug 62 of the plunger and retract the end 58 of the plunger to thereby permit the detent to again move into its feeler holding position.

From the construction thus far described 90 it will be apparent that when the feeler is released by the detent and moves to its feeling position, that the detent itself will be locked or held by the plunger 58 in its inoperative non-engaging position with the 95 feeler and thus permit the feeler to act sensitively in cooperation with the filling. Should the feeler detect a working supply of filling in the shuttle on the following detecting beat or beats, it will be moved front- 100 wardly thereby until the part or shoulder 31 of the feeler passes in front of the detent, at which time the plunger 58 will be withdrawn from under the end of the detent and permit the latter to move into locking 105 engagement with the feeler.

In order that the feeler may be moved frontwardly an amount additional to that caused by a working supply of filling on a detecting beat, the engaging part of the 110 detent is caused to be moved frontwardly as it moves into engaging position with the feeler, so that on subsequent detecting beats the feeler will not engage the filling.

To effect such movement of the detent, the pivotal support 39 carrying the detent fits the bearing 67, Fig. 4, with sufficient looseness to permit the feeler to swing horizontally from the dotted to full line position, as indicated in Fig. 4, as the detent moves to its operative position. To effect such horizontal or frontward movement of the engaging end of the detent, the hook portion 57 of the slide 44 is provided with inclined surfaces 68, 69 which engage the end 42 of the detent, as indicated in Figs. 1, 3 and 5, the result being that when the detent 40 is tripped, as indicated in Fig. 1, by a downward movement of the slide 44 and is locked in its tripped position, the 120 125 130

slide 44 will be moved upwardly after the trip lug 55 has passed the end 54 of the tripping lever and will rise until the stop or stops 53 limit the action of the spring 52, a condition represented in Fig. 5. At this time the detent is still held in its inoperative position, Fig. 5, and when the feeler is moved frontwardly by a working supply of filling and is freed from its lock 10 or plunger 58 it will be turned contra-clockwise, Fig. 5, into engagement with the part or shoulder 31 of the feeler, and during such movement of the detent the end 42 thereof will rest between the two inclined 15 surfaces 68 and 69 of the tripping slide 44, thereby causing the detent to move from its dotted to its full line position, Fig. 4, and impart to the feeler the additional frontward movement, so that on subsequent 20 detecting beats, even with a working supply of filling in the shuttle, the feeler will not engage the filling.

Obviously, the periods of inactivity of the feeler may be varied by variation in the 25 position of the tripping lug 55 connected with the take-up, and likewise the periods of activity of the feeler may be varied by varying the shape or size of the tripping lugs. When, however, the feeler is released 30 to the performance of its feeling function, the detent is held or locked in its inoperative position to avoid any interference with the sensitiveness of the feeler action. Should the feeler meet a working supply 35 of filling in the shuttle during its period of activity, it will be moved frontwardly thereby and free the detent from its holding means, so that the latter may again move into operative position and hold the 40 feeler in its frontward retracted position. As the detent thus moves into its operative position, the engaging end portion of the detent will be moved frontwardly, as hereinbefore described, to give an additional 45 frontward movement to the feeler and hold it out of cooperative relation with the filling during its periods of inactivity.

What is claimed is:

1. In a feeler mechanism for looms, the 50 combination of a feeler, means normally acting to impel the feeler rearwardly into feeling position, a detent for holding the feeler in a frontward inoperative position, means for freeing the feeler from the detent periodically to permit the feeler to move rearwardly into feeling position, a lock for locking the detent in its feeler freeing position until the feeler is moved frontwardly by a working supply of filling on a detecting beat and thereupon 55 unlocking the detent that it may again function to hold the feeler in a frontward inoperative position.

2. In a feeler mechanism for looms, the 60 combination of a feeler, means normally act-

ing to impel the feeler rearwardly into feeling position, a detent for holding the feeler in a frontward inoperative position, means for freeing the feeler from the detent periodically to permit the feeler to move rearwardly into feeling position, a lock for locking the detent in its feeler freeing position until the feeler is moved frontwardly by a working supply of filling on a detecting beat and thereupon 65 unlocking the detent that it may again function to hold the feeler in a frontward inoperative position, and means for causing the detent to withdraw the feeler frontwardly when unlocked from its feeler 70 freeing position.

3. In a feeler mechanism for looms, the combination of a feeler mounted to detect the condition of the filling in the shuttle and to initiate replenishment when the filling is substantially exhausted, a detent, a part carried by the feeler to be engaged by the detent for holding the feeler in frontward inoperative position, means for moving the detent from engagement with said part periodically to permit the feeler to move to rearward feeling position, a lock for holding the detent in feeler freeing position until the feeler is moved frontwardly by a working supply of filling and thereupon freeing the detent that it may again hold the feeler in inoperative 75 position.

4. In a feeler mechanism for looms, the combination of a feeler mounted to detect the condition of the filling in the shuttle and to initiate replenishment when the filling is substantially exhausted, a detent, a part carried by the feeler to be engaged by the detent for holding the feeler in frontward inoperative position, means for moving the detent from engagement with said part periodically to permit the feeler to move to rearward feeling position, a lock for holding the detent in feeler freeing position until the feeler is moved frontwardly by a working supply of filling and thereupon freeing the detent that it may again hold the feeler in inoperative position, and means for causing the detent to withdraw the feeler frontwardly as the detent moves into feeler holding 80 position.

5. A feeler mechanism for looms, comprising, in combination, a feeler, a detent for holding the feeler in frontward inoperative position, means for freeing the detent from holding relation with the feeler after a plurality of picks that the feeler may move to filling engaging position, means for locking the detent in inoperative position, and means for unlocking the detent that it may again hold the feeler in inoperative position.

6. A feeler mechanism for looms, comprising, in combination, a feeler, a detent for holding the feeler in frontward inoperative position, means for freeing the detent from holding relation with the feeler after a plu-

rality of picks that the feeler may move to filling engaging position, means for locking the detent in inoperative position, means for unlocking the detent that it may again hold 5 the feeler in inoperative position, and a part acting upon the detent when it is unlocked to cause the detent to withdraw the feeler frontwardly that it may not engage the filling on subsequent detecting beats until the 10 feeler is again permitted to move to feeling position.

7. A feeler mechanism for looms, comprising, in combination, a feeler, a spring for moving the feeler rearwardly into feeling 15 position, a detent for holding the feeler from spring induced movement, means for freeing the feeler from the detent after a plurality of picks, a lock for the detent to retain it in feeler freeing position, means for 20 tripping the lock when the feeler detects a working supply of filling in the shuttle on a detecting beat and ineffectual to trip the lock when the feeler detects a near approach to substantial exhaustion of filling.

25 8. In a feeler mechanism for looms, the combination of a feeler mounted for movement in a direction longitudinally of the shuttle to effect replenishment of filling when that in the shuttle is substantially exhausted on a detecting beat, a detent for holding the feeler in a frontward inoperative position, means for tripping the detent periodically after a plurality of picks, means for locking the detent in its tripping 30 position, and means rendered effectual by a working supply of filling in the shuttle on a detecting beat for freeing the detent from its locking means that the detent may again hold the feeler in inoperative position.

40 9. In a feeler mechanism for looms, the combination of a feeler mounted for movement in a direction longitudinally of the shuttle to effect replenishment of filling when that in the shuttle is substantially exhausted on a detecting beat, a detent for holding the feeler in a frontward inoperative position, means for tripping the detent 45 periodically after a plurality of picks,

means for locking the detent in its tripping position, means rendered effectual by a working supply of filling in the shuttle on a detecting beat for freeing the detent from its locking means that the detent may again hold the feeler in inoperative position, and means for causing the detent to impart an 50 additional frontward movement to the feeler as the detent moves towards feeler holding position.

10. In a loom, the combination of a feeler to cooperate at times with the filling in the 55 shuttle and initiate a change in the loom operation when substantial exhaustion of filling is detected, a detent adapted to engage the feeler and hold it inoperative in retracted position, means for tripping the detent at intervals to release the feeler, a device for holding the detent out of engagement with the feeler when it is tripped that the feeler may be sensitive to its detecting movement, and means rendered effective to 60 release the detent from said device and permit the detent to again engage the feeler when a working supply of filling is detected by the feeler on a detecting beat.

11. In a loom, the combination of a feeler 65 to cooperate at times with the filling in the shuttle and initiate a change in the loom operation when substantial exhaustion of the filling is detected, a detent adapted to engage the feeler and hold it inoperative in 70 retracted position, means for tripping the detent at intervals to release the feeler, a device for holding the detent out of engagement with the feeler when it is tripped that the feeler may be sensitive in its detecting 75 movement, means rendered effective to release the detent from said device and permit the detent to again engage the feeler when a working supply of filling is detected by the feeler on a detecting beat, and means 80 constructed and arranged to cause the detent to move the feeler frontwardly when the detent is released and engages the feeler.

In testimony whereof, I have signed my name to this specification.

ALONZO E. RHOADES.
